LAMP BASE

Robert L. Martin, 4548 St. Elmo Drive,
Los Angeles, Calif. 90019

Filed Feb. 28, 1967, Ser. No. 5,980

Term of patent 14 years

(Cl. D48—20)

FIG. 1 is a perspective view of the lamp base embodying my new design;

FIG. 2 is a reduced side elevational view of the lamp base, the opposite side being a mirror image thereof; and

FIG. 3 is a top plan view of the lamp base of FIG. 1.

The diagonal surface shading on the base in FIGS. 1 and 2 is representative of an illuminable translucent surface.

The broken line disclosure is for illustrative purposes only.

I claim:

The ornamental design for a lamp base, substantially as shown and described.
